UNITED STATES PATENT OFFICE.

JOSEPH WELLS, OF BROOKLYN, NEW YORK, ASSIGNOR TO ORLANDO A. WILCOX, OF SAME PLACE.

IMPROVEMENT IN PAPER-BAG MACHINERY.

Specification forming part of Letters Patent No. 87,608, dated March 9, 1869.

To all whom it may concern:

Be it known that I, JOSEPH WELLS, of Brooklyn, county of Kings and State of New York, have invented a new and useful Improvement in Machines for Making Paper Bags.

Said invention and improvement relates, first, to regulating automatically the tension or strain on the paper as it is drawn into the machine; second, to mechanism for feeding or drawing the paper in the machine; and, third, to mechanism for pasting the bottom seam or lap of the bag; and I do hereby declare that the following is a full, clear, and exact description of the construction and operation of the same, reference being had to the annexed drawings, making a part of this specification, in which—

Figure 1 is a perspective view. Fig. 2 is a sectional side view. Fig. 3 is an enlarged view of the friction-gland o^2 . Fig. 4 is an enlarged view of the follower M. Fig. 5 is an enlarged view of the forward end of the gage-plate d, showing also the position of the feed-blocks Y Y' Y'' Y''', pulleys a a', and the elastic cords z z'. Fig. 6 is an enlarged view of the upper feed-shaft V with the collars X X'' X'''.

In the manufacture of paper bags by machinery from a continuous roll of paper, it is necessary that the paper be drawn straight and true into the machine and prevented from running off to either side. This result is attained by applying friction or resistance to the spindle carrying the roll of paper, thereby causing a strain or tension upon the paper between the drawing mechanism and the roll, said tension causing the paper to run true in the machine.

When a roll of paper is placed in its proper position in the machine, and a given amount of friction applied to the spindle carrying it, it is obvious that, as the paper is ruled off, the tension upon the paper thus drawn from the roll increases as the leverage of the paper drawn from the roll upon the said roll decreases and the said roll is reduced in size. This varying and increasing tension requires the almost constant attention of the operator to regulate and keep the said tension as nearly uniform as possible.

By my improvement the said tension is rendered self-regulating or automatic, which I will proceed to explain.

Projecting from the back end of the frame of the machine A are two arms B C, supporting a spindle, D, which carries the roll of paper.

Near the outward end of the arm B there is located a friction-gland, o^2 , with its hub passing through and working in the said arm.

Said gland o^2 has a square mortise, s, passing through it to receive the end of the spindle D, squared to fit into said mortise s.

The arm B is also provided with a lever, F, to which it is jointed at the back end, the other end of said lever F passing through the mortise D' and terminating in the shoulder H.

Inside of the lever F is a follower, M, resting against the friction-gland o^2 , and held in its position by the set-screw G, said set-screw also serving to force said follower M against the friction-gland o^2 , thereby producing the required amount of friction and resistance to the spindle D.

The follower is prevented from turning when acted upon by the friction-gland o^2 by the lip R resting against the arm B.

One end of the spindle D is threaded, as is also the flange E, which screws upon it. The flange E' is also made adjustable upon said spindle by a set-screw placed in its hub.

To operate the lever F, there is provided a shaft, V', near the end of which is located a cam, I, with its inside or working edge describing the plane of a right-handed screw, said plane working against the shoulder H. To the other end of the shaft V' is attached a lever, J, by which motion is communicated to the cam I.

There is attached to the end of the lever J a cog-wheel, K, which presses upon the under side of the roll of paper. The object of using a cogged instead of a plain-faced wheel is to prevent the paper from gathering before it, the spaces between the cogs serving to release any slack that may gather before the wheel K.

The office of the spring P is to keep said wheel K pressed against the roll of paper, thereby raising the lever J as the roll of paper is being reduced in size.

If, now, a roll of paper be placed upon the spindle D in such a manner that when unroll-

ing it will turn in the direction indicated by the arrow on the flange E, and firmly secured between the flanges E E', the cog-wheel K resting against its under side, and the end of the paper composing said roll connected with the drawing mechanism of the machine, the requisite degree of tension may be given to the paper to cause it to draw straight and true, by turning up the set-screw G, thereby forcing the follower M against the friction-gland o².

The operation of drawing the paper from the roll being continued, said roll is gradually reduced in size, thereby gradually permitting the spring P to raise the lever J, by which movement the cam I is caused to release its pressure upon the shoulder H, causing the friction upon the friction-gland o² to be gradually reduced, thereby causing, automatically, a nearly uniform tension or strain upon the paper as it is drawn into the machine, until said roll is exhausted.

I will now proceed to explain the drawing mechanism referred to heretofore.

The gage-plate d is constructed with two or more longitudinal openings, o o' o'' o''', in its forward end, which are rabbeted down on either side one-half the thickness of said gage-plate d, to form a bearing upon which the feed-blocks Y Y' Y'' Y''' slide, and are of such a length that the said feed-blocks may perform their full stroke without coming in contact with the end of the gage-plate d. The said feed-blocks are constructed so as to fit into the said openings and move easily, and are about one-half of the length of said openings, and slightly thicker than the said gage-plate. Each pair of said feed-blocks is connected by an elastic cord, z z', passing around the pulleys a a', respectively, said pulleys being placed in openings made in the gage-plate for their reception, and are covered by the plate b, a part of which is seen broken off in the perspective view.

The said elastic cords z z' are of such a length that, when one feed-block has nearly completed its forward stroke, the other will be drawn back to the end of its respective opening.

Situated below the said gage-plate, and at a right angle with it, and in the middle of the length of the said openings, is a drawing-roller, W, the circumference of which is somewhat less than the length of the said openings o o' o'' o''', its length extending across the said gage-plate.

Situated above the said drawing-roller W, with which it is connected by the gear-wheels, of equal size, T U, is located a drawing-shaft, V, upon which is placed, corresponding with the said openings in the gage-plate d, two or more collars, X X' X'' X''', of equal diameter with the drawing-roller W, with nearly one-half of the periphery of each removed, and are set on the drawing-shaft V in pairs, as shown in Fig. 6, one of each pair being set

opposite to the other. The said feed-blocks are kept in their respective openings in the gage-plate d by a cross-bar, c, which extends across the machine immediately above said gage-plate, with just sufficient room for the paper to pass freely between it and the said feed-blocks.

If, now, the paper, which envelops the gage-plate d in the process of the manufacture, be drawn forward and presented to the drawing-roller W and the collars X X' X'' X''', and they put in motion by the crank w and its proper connections, it will be grasped by the said collars in each pair alternately, and drawn forward, the acting collar pressing the paper and its respective feed-block upon the lower drawing-roller W, causing a forward movement of the feed-block until its stroke is completed, when it is released by the acting collar, and is then drawn back by the forward movement of the other feed-block of the pair operating the elastic cord connecting them. In order to insure the continuous action of a pair of the said collars, one of said collars is caused, by its periphery containing a little more than one-half of its circumference, to grasp its respective feed-block just before the other feed-block of the pair has completed its full forward stroke, causing both of the said feed-blocks to move forward for a short distance together, the said elastic cord permitting such movement by its elasticity. The requisite degree of pressure to operate the said feed-blocks between the said drawing-roller and the said collars may be produced by screwing down the caps A' A'', or by providing sliding boxes for the journals of the said drawing-roller W and feed-shaft V, and adjusting them by set-screws.

The construction of the pasting mechanism is substantially as follows:

Forward of the folding-rollers g' g'', and raised a little above them, is located a shaft, n, extending across the machine. This shaft is provided with two arms, c' c'', which support a pasting-roller, l, and is operated by a lever, P', attached to one of its outer ends, said lever P' being connected with the rods r, lever t, by which the movement of the cam u is communicated to the pasting-roller l, bringing said pasting-roller l from the paste-roller m down on to the supporting-plate f', its upward movement to the said paste-roller m being caused by the spring v. Situated forward of the said pasting-roller l, and running parallel with it, is a paste-roller, m, revolving in a pan, e', for containing the paste, and is operated by a belt, h, driven by a pulley, x, attached to the main shaft e and pulley z. Located on the shaft of the said paste-roller m is a gear-wheel, k, working into a loose gear-wheel, j, placed upon the outer end of the shaft n. Working into the said gear-wheel j is also a gear-wheel, i, attached to the shaft of the pasting-roller l. The object of placing the gear-wheel j upon the shaft n is that the

pasting-roller *l* may vibrate back and forth between the said paste-roller *m* and the supporting-plate *f*, and not separate or disturb the pitch-line of the said gear-wheels *i j*, and also that the said pasting-roller *l* may be made to revolve continuously without respect to its position between said paste-roller *m* and the supporting-plate *f*. The supporting-plate *f'* extends across the machine immediately above the folding-roller *g''*, and very near it, its inside edge conforming nearly to the circumference of said folding-roller *g''*, in order that the end of the tube or bag may pass freely upon it to be pasted.

If, now, the tube or bag, as it has passed forward from the drawing mechanism, and has been severed by appropriate means, so as to leave a projecting lap on its under side, passes forward onto the said supporting-plate *f'*, (the machine being in operation,) by the action of the cam *u*, located on the main shaft *e*, the pasting-roller *l* is brought down onto the projecting lap of the bag, and applies to it the paste, the said supporting-plate *f'* supporting the said lap during the operation of pasting it, when it is forced by the blade *z'* between the folding-rollers *g' g''*, and the said lap folded onto the bag. After applying the paste to the

said lap by the action of the cam *u* and spring *v*, the said pasting-roller *l* is brought back against the said paste-roller *m*, against which it revolves in receiving its supply of paste.

What I claim as my invention, and desire to secure by Letters Patent, is—

1. Regulating the tension or strain on the paper, as it is drawn into the machine, in the process of making paper bags, by means of a self-adjusting compressor-bar and wheel applied thereto, substantially as described.

2. Drawing the paper tube forward to the cutting and pasting devices by means of a shaft, *V*, fitted with collars, in combination with feed-blocks, drawn back by elastic cords, substantially as described.

3. The combination of the bar *C* with the feed-blocks, for the purpose of keeping them in their respective places in the gage-plate, substantially as described.

4. Laying the paste upon the edge of the paper to be pasted, by means of a revolving and vibrating pasting-roller, operated substantially in the manner described.

JOSEPH WELLS.
